FUSE LINK EXPELLING MEANS

William O. Schultz, South Milwaukee, and Chester W. Brown, Milwaukee, Wis., assignors to Line Material Company, South Milwaukee, Wis., a corporation of Delaware

Application March 10, 1937, Serial No. 130,054

13 Claims. (Cl. 200—127)

This invention relates to improvements in fuse link-expelling means for expulsion fuses.

It is an object of this invention to provide for expulsion fuses, link-expelling means comprising a spring-actuated lever adapted to withdraw the fuse link from the tube in a path extending longitudinally from the end thereof.

Another object of this invention is to provide a spring-actuated lever for expelling a fuse link from a cartridge and adapted to clampingly engage the fuse link while the latter is under tension and to release the fuse link after the link has been withdrawn from the cartridge.

A further object is to provide for standard expulsion fuses, fuse link-expelling means providing the above-noted features and adapted for detachable connection with the fuse, thereby preventing old expulsion fuses from becoming obsolete.

20 A still further object is to provide a fuse link-expelling device in which the expelling lever is movable radially on its pivot against the action of its biasing spring, thereby to permit a fuse link to be engaged clampingly by the lever after 25 the lever has been moved to link-tensioning position.

Figs. 1 to 3, inclusive, are substantially identical with those shown in the copending application of William O. Schultz, Serial Number 130,055, filed March 10, 1937, for Fuse link throw-out devices.

In the drawings:

Fig. 1 is a side elevation illustrating a preferred form of this invention.

25 Fig. 2 is a fragmentary view in side elevation of the device shown in Fig. 1 after it has operated.

Fig. 3 is a lower end view of the device shown in Fig. 1.

40 Fig. 4 is a fragmentary view in side elevation illustrating a modified form of this invention.

Fig. 5 is a fragmentary view in side elevation illustrating the device shown in Fig. 4 after it is operated.

45 Fig. 6 is a view of the fuse link-removing mechanism before it is removed from the tube and taken from the left-hand side relative to Fig. 5.

Like parts are identified by the same reference characters throughout the several views.

50 In all of the expulsion fuses shown in the drawings, the fuse comprises a cartridge 1 having an upper contact ferrule 2, closure cap 3, lower contact ferrule 4 spaced from the lower open end of the tube and provided with a depending clamp-55 ing arm 5, and a clamping screw or bolt 6 and

a fuse link 7 disposed in the tube for electrically connecting the upper contact ferrule 2 and the lower contact ferrule 4. The clamping arm 5 is provided with a clamping lug 8 which is slotted at 9 in a vertical direction and longitudinally 5 relative to the cartridge 1. The clamping lug 8 is also provided with a threaded recess extending toward the base of the slot 9 and adapted to receive the threaded end of the clamping bolt 6.

10 In the preferred form of the throwout device illustrated in Figs. 1 to 3, inclusive, a hollow sleet hood 10 is provided with a supporting arm 11 having a vertically extending portion 12 positioned in the slot 9 and removably secured therein by means of the clamping bolt 6. The sleet hood 10 is also provided with a recessed apron or skirt 13 extending below the arm 11 and with a clamping jaw 14 extending in a horizontal direction laterally from the lower margin of the 20 skirt. As shown, this jaw 14 is provided with an arcuate clamping face upon its under side. The skirt 13 is provided with a pivot pin 15 extending to the interior of the skirt for supporting the lever as will hereinafter appear.

25 The throwout lever 16 comprises a link-tensioning arm 17 provided with a link-engaging finger 18, a spring-engaging arm 19 provided with a spring-receiving aperture 20, a pivot-engaging arm 21 extending to the interior of the 30 apron 13 and provided with an elongated slot 22 slidably receiving the pin 15, and a clamping jaw 23 cooperating with the clamping jaw 14 for securing the fuse link 7 therein as will hereafter appear. As shown, the clamping jaw 23 is provided with an arcuate clamping surface offset from the arcuate clamping surface on the clamping jaw 14. The link-engaging arm is provided with a reinforcing rib 24 on the lower side thereof.

35 The throwout lever 16 is biased to the position shown in Fig. 2 by means of a coil spring 25 engaged at one end in the aperture 20 of the lever and at its other end 26 with the bottom of the hollow or recess 27 in the hood 10. Thus the spring is extended into the hood and is protected against sleet formation which would tend to hamper the contractile action of the spring.

40 The throwout lever 16 naturally assumes the position shown in Fig. 2. When the fuse link 7 is placed in the tube 1 as shown in Fig. 1, it will 45 be passed beneath the finger 18 of the lever 16 to hold the lever in the position shown and will then be placed between the clamping jaws 14 and 23. In order to facilitate the placing of the fuse link between the clamping jaws 14 and 23, the 55

slot 22 in the arm 21 of the throwout lever 16 is provided. This slot 22 permits the throwout lever 16 to be moved downwardly on the pin 15 relative to Fig. 2 for the purpose of separating 5 the clamping jaws 14 and 23. When these jaws have been separated sufficiently, the link may then be placed between them and upon release of the lever 16, the spring 25 will clamp the jaws to the link 7.

10 It will be observed that the spring-engaging arm 19 on the lever 16 is extended in a horizontal direction to the right relative to Fig. 1. This extended portion 19A serves as a means for manually moving the lever 16 to separate the 15 jaws 14 and 23. It will be further observed that the link-engaging finger 18 on the lever 16 is directly beneath the cartridge 1. Consequently, when the jaws 14 and 23 are separated by 20 pressing down on the portion 19A, the finger 18 will contact the end of the cartridge and serve as a pivot point while the link 7 is being inserted between the jaws.

Although the finger 18 is not shown in contact with the lower end of the cartridge, nevertheless, 25 it will be obvious that its position relative to the cartridge when in link-stressing position, will be a matter of choice when the link is mounted in the cartridge.

Fig. 2 illustrates the portion 19A on the lever 30 16 in contact with the lower margin of the hood 10, thereby serving as a stop defining the final position of the lever after the link 7 has been withdrawn from the cartridge.

The device illustrated in Figs. 1 to 3, inclusive, 35 operates as follows: Assuming that the fuse link 1 has been tensioned as illustrated in Fig. 1, and that an overload has destroyed the upper end of the fuse link (not shown), the spring 25 will cause the lever to rotate about the pin 15 and 40 thereby move the fuse link in a path extending downwardly and arcuately from the lower end of the tube 1. When the lever 16 has moved a given distance in the path indicated, the jaws 14 and 23 will be separated sufficiently to permit 45 the link to drop from the structure, thereby clearly indicating that the circuit through the fuse has been opened.

A modified form of the invention disclosed 50 herein is shown in Figs. 4 to 6, inclusive. Fig. 4 discloses the device in operative position relative to the tube 1, the clamping bolt 6 and the fuse leader 7. The supporting arm 28 is bent to provide a vertical section 30 and upper and lower 55 angularly extending portions 30A and 30B, the upper end of the upper portion 30A being provided with an aperture 29A adapted to receive the upper end of the spring 29 and the lower end of the lower portion 30B being formed into two spaced supporting fingers 31-31, each finger 60 being provided with vertically extending elongated slots 32 as shown in Fig. 4. A pivot pin 33 extends between the fingers 31-31 and is slideable in the elongated slot 32.

A throwout lever 34 is pivotally mounted on pin 65 33 and is provided with a link-engaging finger 35 adapted to receive the leader 7 and hold it in alignment with the throwout lever 34. Formed as an integral part of the throwout lever, is a resilient finger 36A extending in an arched path 70 above the broad section 37A of the throwout lever 34. The throwout lever or channel member 34 has tapered sides 34A, one of which is cut away to provide a slot 35A. The bottom of the channel member 34 is slotted at 36 to provide a clamping 75 finger 36A and a bridge 38A. The bridge section

33A is provided with an aperture 38 adapted to receive the lower portion of spring 29. The sides 34A of the lever are connected by a pivot pin 33 extending laterally from the sides and through the slots 32 in the fingers 31-31.

The operative relation of the fuse leader 7 and the throwout lever 34 is clearly shown in Fig. 4. The leader 7 extending from the bottom of the fuse tube 1 is passed under the link-engaging finger 35, passed up through the opening 35A and between the two pivot-supporting legs 31, this last passageway being enlarged by the downward movement of the throwout lever in the radial slots 32, thus providing more clearance between the resilient finger 36A and the contact face 37. The tension spring 29 mounted between the two apertures 29A and 38 provides a clamping action on the leader 7 between the contact surface 37 and finger 36A and transmits a throwout action at the link-engaging finger end on the leader 7.

20 After a predetermined overload has acted on the fuse link, the throwout device throws the leader 7 downwardly free from the tube while the throwout lever describes an arcuate path downward and away from the end of the tube 1. 25 When this action has taken place, the device is in the position shown in Fig. 5. As the lever 34 moves away from the tube end about the pivot pin 33, the clamping action of the finger 36A against the contact face 37 is destroyed, which 30 permits the leader to drop from the structure, thereby providing a clear indication that the circuit through the fuse has been opened.

The device shown in Figs. 4 to 6, inclusive, is modified from that shown in Figs. 1 to 3, inclusive, in that the radial slot 32 is placed on the supporting fingers 31 of the supporting arm 28, while the radial slot 22 in Figs. 1 to 3, inclusive, is placed in the pivot-engaging arm 21 of the throwout lever 16. Another difference is noted 40 in the exposure of the tension spring 29 in Figs. 4 and 5 and the attachment of the upper end of the spring with the upper portion of the supporting arm 28 different from the encased spring 25 shown in Figs. 1 and 2 and the attachment of its upper end with the hood 10.

From the foregoing it will be apparent that a fuse link throwout device for expulsion fuses has been provided which pulls the link in an axial direction relative to and exteriorly of the tube, thereby producing a minimum flexing of the link as it leaves the tube. It will also be seen that the throwout device provides a positive release of the link after the latter is removed from the tube and thereby permits the link to drop from the fuse structure. Furthermore, the means for releasing the link provides a simple, movable clamp for the protruding end of the link, enabling easy assembly of the link in operative position.

Obviously, the throwout device herein disclosed 60 can be cheaply manufactured and provides suitable protection of the movable parts from sleet and damage.

In addition to the principal objects of the invention heretofore disclosed, it will be apparent 65 that we have provided a throwout device in which the lever biasing spring 25 (Figs. 1 and 2) and 29 (Figs. 4 and 5), as well as the throwout lever 16 (Figs. 1 and 2) and 34 (Figs. 4 and 5) are not subjected to destructive full line currents because 70 fuse links tensioned thereby are held in direct electrical connection with the pivot support.

We have also provided a throwout device in which the throwout lever assumes a predetermined position after it has withdrawn a fuse link 75

and in which the clamping action of the throw-out lever is not dependent upon the thickness of the material or the kind of material of the lever. That is, the lever may be made very sturdy and 5 need not be made of metal, although such may be preferred.

Another feature which will be apparent from the foregoing disclosure is in the novel arrangement of the lever supporting pivot means whereby the projecting ends of the fuse links may be positioned between the clamping jaws regardless of the transverse dimension of the link and without changing the point of application of the throwout lever.

15 We claim:

1. A fuse link throwout device for expulsion fuses, said device comprising a supporting member having a link-clamping portion, a throwout lever pivotally mounted on the support for tensioning said link and having a link-clamping portion cooperatively related to said clamping portion on said support, and a spring secured at one end to said support and at the other end to said lever, said clamping portions being upon 20 a side of the pivotal mounting of said lever opposite to that on which said spring is secured to said lever, whereby said spring holds said clamping portions operative while said lever tensions said link and moves said lever from clamping 25 position after said fuse link is severed.

2. The combination with an expulsion tube and a fuse link extending therefrom, of a fuse link throwout device supported by said tube and comprising a support secured to the tube and 30 having a link-clamping portion, a throwout lever pivotally mounted on the support and having a clamping portion operatively related to said clamping portion on said support, and a spring having one end engaged with the support and 35 the other end engaged with said lever, said clamping portions being upon a side of the pivotal mounting of said lever opposite to that on which said spring is secured to said lever, said lever being engaged with said fuse link to pull 40 said link from said tube and clamping the extending portion of said link to said support, said spring holding said clamping portions operative while said lever tensions said link and biasing 45 said lever to pull said link from said tube and cause separation of said clamping portions when 50 said fuse link is severed, whereby to release said fuse link from clamping position between said lever and said support.

3. The combination with an expulsion tube 55 and a fuse link extending therefrom, of a fuse link-expelling device comprising a support mounted on said tube, a throwout lever pivotally mounted on said support, the pivotal mounting of said lever being movable in a radial direction 60 relative to the pivot axis, a spring coating between said support and throwout lever, said lever engaging said fuse link and being biased by said spring to pull said fuse link from said tube, said lever clampingly engaging said fuse link to said 65 support and being biased to clamping position by said spring while said lever is engaged with said link.

4. A fuse link throwout device for expulsion fuses, said device comprising a support adapted 70 for attachment to a fuse cartridge, a throwout lever pivotally mounted intermediate its ends on said support to provide a fuse link-engaging arm on one side of the pivot and a lever-actuating arm on the other side of said pivot, and a spring 75 engaged at one end with said support and at the

other end with said lever-actuating arm, said lever and support having cooperating clamping portions for securing a fuse link thereto when said link-engaging arm is engaged with said fuse link.

5. A fuse link throwout device for expulsion fuses, said device comprising a support adapted for attachment to a fuse cartridge, a throwout lever pivotally mounted intermediate its ends on said support to provide a fuse link-engaging arm 10 on one side of the pivot and a lever-actuating arm on the other side of said pivot, and a spring engaged at one end with said support and at the other end with said lever-actuating arm, said lever and support having cooperating clamping 15 portions for securing a fuse link thereto when said link-engaging arm is engaged with said fuse link, the pivotal mounting of said lever being movable in a direction laterally of the pivot axis to facilitate clamping engagement of said fuse 20 link.

6. A fuse link throwout device for expulsion fuses, said device comprising a support adapted for attachment to a fuse cartridge, a throwout lever pivotally mounted intermediate its ends 25 on said support to provide a fuse link-engaging arm and a lever-actuating arm, a spring connected at one end with said support and at the other end with said lever-actuating arm, and means for clampingly engaging a fuse link when 30 said link-engaging arm is engaged therewith, said means being upon a side of the pivotal mounting of said lever opposite to that on which said lever-actuating arm is positioned.

7. A fuse link throwout device for expulsion fuses, said device comprising a support adapted for attachment to a fuse cartridge, a throwout lever pivotally mounted intermediate its ends on said support to provide a fuse link-engaging arm and a lever-actuating arm, a spring connected 40 at one end with said support and at the other end with said lever-actuating arm, and means for clampingly engaging a fuse link when said link-engaging arm is engaged therewith, said means being upon a side of the pivotal mounting 45 of said lever opposite to that on which said lever-actuating arm is positioned, the pivotal mounting of said lever being movable in a direction laterally of the pivot axis.

8. In combination with a fuse cartridge having 50 an open end and a fuse link projecting therefrom, a fuse link throwout device comprising a support secured to said cartridge, a throwout lever pivotally mounted intermediate its ends on said support to provide a link-engaging arm to 55 engage with said link and a lever-engaging arm, a spring secured at one end to said support and at the other end to said lever-engaging arm and biasing said lever to pull said link from said tube, said link-engaging arm being movable in an arc 60 extending tangentially from the open end of said tube, thereby to pull said link from said tube with a minimum flexing thereof, and means for clamping the projecting portion of said link to 65 said support.

9. In combination with a fuse cartridge having 70 an open end and a fuse link projecting therefrom, a fuse link throwout device comprising a support secured to said cartridge, a throwout lever pivotally mounted intermediate its ends on said support to provide a link-engaging arm to engage with said link and a lever-engaging arm, a spring secured at one end to said support and at the other end to 75 said lever-engaging arm and biasing said lever

to pull said link from said tube, said link-engaging arm being movable in an arc extending tangentially from the open end of said tube, thereby to pull said link from said tube with a minimum flexing thereof, and means for clamping the projecting portion of said link to said support, the pivotal mounting of said lever being movable in a direction laterally of the pivot axis, thereby to facilitate clamping of said link.

10. In combination with a fuse cartridge having an open end and a fuse link projecting therefrom, a fuse link throwout device comprising a support secured to said cartridge, a throwout lever pivotally mounted intermediate its ends on said support to provide a link-engaging arm to engage with said link and a lever-engaging arm, and a spring secured at one end to said support and at the other end to said lever-engaging arm and biasing said lever to pull said link from said tube, said link-engaging arm being movable in an arc extending tangentially from the open end of said tube, thereby to pull said link from said tube with a minimum flexing thereof, said support and lever having cooperating clamping portions for clamping the projecting end of said link therebetween.

11. In combination with a fuse cartridge having an open end and a fuse link projecting therefrom, a fuse link throwout device comprising a support secured to said cartridge, a throwout lever pivotally mounted intermediate its ends on said support to provide a link-engaging arm to engage with said link and a lever-engaging arm, and a spring secured at one end to said support and at the other end to said lever-engaging arm and biasing said lever to pull said link from said tube, said link-engaging arm being movable in an arc extending tangentially from the open end of said tube, thereby to pull said link from said tube with a minimum flexing thereof, said support and lever having cooperating clamping portions for clamping the projecting end of said link therebetween, the pivotal mounting of said lever being movable in a direction laterally of the pivot axis and biased against said movement by said spring, thereby to facilitate clamping of said link and to thereafter hold said link in clamped position.

12. In combination with a fuse cartridge having an open end and a fuse link projecting therefrom, a fuse link throwout device comprising a support secured to said cartridge, a throwout lever pivotally mounted intermediate its ends on said support to provide a link-engaging arm to engage with said link and a lever-engaging arm, and a spring secured at one end to said support and at the other end to said lever-engaging arm and biasing said lever to pull said link from said tube, said link-engaging arm being movable in an arc extending tangentially from the open end of said tube, thereby to pull said link from said tube with a minimum flexing thereof, said support and lever having cooperating clamping portions for clamping the projecting end of said link therebetween, the pivotal mounting of said lever being movable in a direction laterally of the pivot axis and biased against said movement by said spring, thereby to facilitate clamping of said link and to thereafter hold said link in clamped position, said clamping portion automatically releasing said link when the latter is pulled from said cartridge.

13. The combination with a fuse cartridge having an open end and a fuse link projecting therefrom, of a throwout device comprising a supporting arm secured to said cartridge, a throwout lever pivotally mounted on said arm and having a link-tensioning position, the pivotal connection between said arm and lever being disposed in a plane normal to and adjacent the end of said cartridge, said lever being slidable on said pivot in a direction paralleling said cartridge, a clamping jaw on said arm and a cooperating clamping jaw on said lever and beneath the other jaw, said jaws being substantially normal to the sliding path of said lever and relatively below said pivot, said jaws clampingly engaging said fuse link and extending laterally relative to said arm and lever, said lever engaging and tensioning said fuse link adjacent said open end, and a spring coacting between said arm and lever to hold said jaws in clamping relation and urging said lever to pull said link from said tube.

WILLIAM O. SCHULTZ.
CHESTER W. BROWN.
